Primary Examiner — Cynthia R Underwood

CLAIM

The ornamental design for the corner pulley as shown and described.

DESCRIPTION

FIG. 1 is a front, right, and top perspective view of the corner pulley, showing my new design;

FIG. 2 is a rear, left, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines depict portions of the corner pulley that form no part of the claimed design.
